FIRE DETECTOR OR THE LIKE

Lewis G. Blevins, Odon, Ind., assignor to B.R.K. Electronics, Inc., Skokie, Ill., a corporation of Illinois

Filed July 8, 1965, Ser. No. 86,069

Term of patent 3½ years

(Cl. D72—1)

FIGURE 1 is a perspective view of a fire detector showing by new design;

FIGURE 2 is a side elevation thereof; and

FIGURE 3 is a bottom plan view thereof.

The top of the fire detector is substantially plain.

I claim:

The ornamental design for a fire detector or the like, substantially as shown and described.
